UNITED STATES PATENT OFFICE.

EDWIN H. COLPITTS, OF EAST ORANGE, NEW JERSEY, ASSIGNOR TO WESTERN ELECTRIC COMPANY, INCORPORATED, OF NEW YORK, N. Y., A CORPORATION OF NEW YORK.

TELEPHONE TRANSMISSION SYSTEM.

1,200,082.

Specification of Letters Patent.

Patented Oct. 3, 1916.

Application filed December 27, 1915. Serial No. 68,845.

To all whom it may concern:

Be it known that I, EDWIN H. COLPITTS, a subject of the King of Great Britain, residing at East Orange, in the county of Essex and State of New Jersey, have invented certain new and useful Improvements in Telephone Transmission Systems, of which the following is a full, clear, concise, and exact description.

10 This invention relates to telephone transmission systems, and more particularly to the operation of repeaters on loaded lines. Its object is to increase the amplification at which a telephone repeater may operate 15 with stability under practical loaded line conditions. This object is accomplished by a suitable correlation of the repeater and line characteristics, giving rise to a certain necessary relation between these characteristics which does not obtain in repeaters as hitherto employed. The nature of this relation will be made apparent from the following discussion of the methods and limits 20 of operation of repeater sets. In this discussion, reference will be made to the drawings, in which—

Figure 1 represents a repeater circuit employing two repeaters and arranged to give two-way amplification over a loaded circuit; Figs. 2, 3 and 4 give curves showing certain loaded line and repeater characteristics which must be taken into consideration if repeaters are to be operated effectively in connection with loaded lines; 35 and Figs. 5 and 6 show certain details of construction whereby a repeater may be made suitable for use in connection with loaded lines.

Referring to Fig. 1, there is illustrated 40 a repeater station at which two telephone lines 2 and 3 terminate. These telephone lines are loaded at regular intervals in the well-known manner by means of the loading coils 4, and have therefore what is 45 known as a lumped inductance. 5 and 6 are artificial lines or networks designed to balance the lines 2 and 3 respectively for impedance. Midway between the line 2 and the artificial line 5 is bridged the winding 50 7 of the repeater coil 8, the secondary of which leads to the actuating winding 10 of a telephone repeater of the receiver-microphone type. Telephonic currents therefore, coming in from the station 11 over the line 55 2, will flow through winding 10 of repeater

A and actuate the microphone element 12, thereby sending out amplified telephone currents through the windings 13 of the output transformer 14, whose secondary windings 15 are included in series with the conductors of line 3 leading to the station 16. Similarly, telephone currents originating at station 16 will actuate the winding 17 of repeater B by way of transformer 18, and by actuating microphone 19 will send out 60 amplified currents to the station 11 by way of the repeating coil 20.

If the impedance 5 is an exact copy of the impedance of line 2, no difference of potential will be set up across the terminals of the winding 7 by currents flowing in primary 21 of the repeating coil 20, inasmuch as the secondary windings 22 are symmetrically disposed on either side of the point at which winding 7 is connected. Similarly, if the 70 artificial line 6 has an impedance equal to that of line 3 for all frequencies, and if the windings 15 of transformer 14 are symmetrically disposed with respect to the primary of the repeating coil 18, a condition 75 of stability is obtained. It may, however, be shown theoretically, and is also well known in practice, that if each balancing network is not exactly equivalent at all frequencies to its corresponding line, a condition will be set up in which one repeater feeds power back into the other, resulting in a local circulation of power in the repeater station. When this unbalancing of 80 lines and network becomes sufficiently large, the power circulation becomes cumulative, giving rise to an unstable operation which is called singing, and which destroys the usefulness of the device. It is further 85 known that the relation between the amplifying power of the repeaters and the allowable unbalance between artificial balancing lines and actual lines is a reciprocal one, so that if U_1 and U_2 are the impedance unbalances of the two lines and their networks, and if A_1 and A_2 are the amplifying powers of the two repeaters, these quantities 90 are related by the equation

$$\frac{1}{A_1 A_2 \alpha \sqrt{U_1 U_2}}$$

Thus, the maximum amplifying power which may be used is limited by the closeness with which the lines and networks may be balanced, and in practice this is what 110

limits the "gain" which may be made with any kind of repeater. If, for any reason, the line conditions are such that an accurate balance cannot be obtained and singing results, the non-singing condition can be restored by impairing somewhat the amplifying power of the system. A convenient way of doing this is by inserting in the output circuit of the repeaters a shunt 23 by which the amount of energy delivered by repeater A, for example, to line 3 is limited. Such a shunt preferably may be in the form of an Ayrton shunt, having a variable shunt member 24 and a variable series member 25, the steps of which are so arranged as to keep the total impedance of the repeater, as viewed from the terminals of the transformer winding 13, constant.

Now, in practice, the impedance of a loaded line changes with frequency in the manner shown by the full line curve of Fig. 2, which represents the relation between frequency f and line impedance Z . It is found impossible to exactly simulate this impedance by means of a balancing network, although its average trend (as shown by the dotted line) may be imitated in the balancing network. There is, therefore, always a certain amount of unbalance at some frequencies, even in the most carefully constructed lines. This causes a serious limitation on the amplifying power which may be used, particularly with a repeater which has unequal amplifications at different frequencies, for in this case the amplification must be made so small that at the frequency of the most efficient operation of the repeater, the conditions implied in the above equation shall not be violated. The object of the present invention is to so relate the repeater and loaded line characteristics that this difficulty may be minimized.

The curve of Fig. 3 shows the relation between the frequency f and the amplifying power A of a repeater of the receiver-microphone type. It will be noted that the point of most efficient amplification lies at a certain definite frequency (f_r), which is the frequency of resonant response of the vibrating system. Now in any loaded line, such as the line 2 or 3 illustrated in Fig. 1, having lumped inductance L and distributed capacity C , the attenuation offered to currents in the line is related to the frequency of these currents by a relation which is shown graphically in Fig. 4. It will be noted that the attenuation has a small value for a considerable range of frequencies, and that it rises rather abruptly at a certain value of frequency, which may be shown theoretically to be equal to

$$\frac{1}{\pi\sqrt{LC}}$$

In this formula, L and C are respectively

the inductance and capacity per loading section of the loaded line.

A comparison of the curves of Figs. 3 and 4, which represent respectively characteristics of the repeater and of the line, will show that if the resonant frequency f_r is made to fall below the frequency f_L at which the line begins to offer a high attenuation, the average amplification allowable in the repeater will be small, since the peak of the curve of Fig. 3 must be low enough to insure that no singing occurs at that amplification. The amplification over the rest of the range will, therefore, be restricted to a much smaller value. On the other hand, if the resonant frequency f_r of the repeater is made to fall outside the range of free transmission of the loaded line, that is, if f_r is made considerably greater than

$$\frac{1}{\pi\sqrt{LC}}$$

any tendency to sing at the frequency f_r is resisted by a greatly increased value of attenuation in the loaded line, and the average amplification allowable over the range of free transmission is much increased. Moreover, the amplification at various frequencies inside the range of free transmission is made much more uniform because the curve of Fig. 3 is approximately straight, except in the neighborhood of the resonant frequency of the repeater. In operating such a resonantly responsive repeater on a loaded line, it is therefore essential for high efficiency that the resonant frequency be considerably higher than the frequency at which the line begins to offer an increasing attenuation. Where this so-called cutoff frequency is in the neighborhood of 2200 periods per second, as in the case of the average loaded line, a repeater having a moving system, such as that illustrated in Figs. 5 and 6, has been found capable of producing the desired result. In this repeater the moving system consists of the corrugated metal diaphragm 30, which acts as the movable electrode for the transmitter element 31, and has at its center a short iron plunger 32 which serves as an armature for the electromagnet of the receiver element 33. The details of this repeater structure need not be entered into, as they will be found fully described in Shreeve Patent No. 1,156,636.

It will be noted in connection with Fig. 1 that the repeaters A and B have, in addition to the actuating windings 10 and 17 respectively, magnetizing windings 26 and 27 and differential windings 28 and 29, whose functions need not be discussed here, as complete description will be found in Shreeve Patent No. 1,159,603 of November 9, 1915.

What is claimed is:

1. In a transmission system, the combination with line conductors capable of trans-

mitting efficiently electric current within only a limited range of frequencies, of a repeater for reinforcing said currents and having a moving system whose natural period of vibration lies outside of said range.

2. In a telephone transmission system, the combination with a loaded line, of a telephone repeater having a moving system whose natural period of vibration is greater than the cutoff frequency of said loaded line.

3. In a telephone transmission system, the combination with a telephone line having distributed capacity and lumped inductance, of an artificial line having an impedance characteristic equivalent to the average impedance of said line for the range of frequencies which said line transmits efficiently, and a telephone repeater having a moving system whose natural period of vibration lies outside said range of frequencies.

4. In a telephone transmission system, two telephone lines, each having distributed capacity and lumped inductance, an artificial line for each of said lines and having an impedance characteristic equivalent to the average impedance of the telephone line individual thereto for the range of frequencies which said line transmits effectively, and two telephone repeaters connecting said lines, each of said repeaters having a moving system whose natural period of vibration lies outside said effective range of either of said lines.

5. In a telephone transmission system, two loaded lines, an artificial line connected to each of said lines and having an impedance equivalent to that of the loaded line to which it is connected, and two telephone repeaters connecting said loaded lines, each of said

repeaters having a moving system whose natural period of vibration is greater than the cutoff frequency of said loaded lines.

6. In a telephone transmission system, two loaded lines each terminating in a balancing artificial line, in combination with two telephone repeaters having input circuits and output circuits, each of said repeaters having its input circuit connected to one of said loaded lines and its output circuit connected to the other of said loaded lines respectively, and having a moving system whose natural period of vibration is greater than the cutoff frequency of said loaded lines.

7. In a telephone transmission system, a repeater station, two telephone lines having lumped inductance and distributed capacity terminating at said station, an artificial line individual to each of said lines and adapted to balance the average impedance of said line throughout its effective transmitting range, two telephone repeaters having input circuits and output circuits, the input circuit of one of said repeaters being connected to the first of said lines and its output circuit being connected to the second of said lines, the input circuit of the other of said repeaters being connected to the second of said lines and its output circuit being connected to the first of said lines, each of said repeaters having a moving system whose natural period of vibration lies outside the said effective transmitting range of said telephone lines.

In witness whereof, I hereunto subscribe my name this 23rd day of December, A. D. 1915.

EDWIN H. COLPITTS.
